UNITED STATES PATENT OFFICE

CLARENCE FLINT, OF BIRMINGHAM, ENGLAND

FASTENER FOR PURSES, HAND BAGS, ATTACHE CASES, OR THE LIKE

Application filed November 6, 1926, Serial No. 146,644, and in Great Britain January 20, 1926.

This invention relates to locks or fasteners for purses, bags, attaché cases or the like, and has for its object to make provision for receiving the name and address or other 5 identification mark of the owner.

The invention consists in providing the one part of the lock or fastener with a holder adapted to receive or to contain a card, label or device upon which the name and address 10 of the owner may be written, or which may bear an identification mark of the owner. The card or label holder is preferably carried by that part of the fastening which is secured to the body of the receptacle, being arranged 15 in such a manner that the card or label is covered by the flap of the receptacle when the latter is closed. The fitting is thus particularly suitable for attachment to purses, hand bags or the like where a prominently dis- 20 played name is to be avoided. By raising the closure flap, however, the ownership of the purse or bag may be at once ascertained. The card holder may be carried by the socket element of the fastening, which may be pro- 25 vided with an extension carrying guide flanges adapted to receive the card, and the latter may be protected by a celluloid covering.

Figure 1 of the accompanying drawings 30 shows a hand bag in which the part of the fastener upon the body of the bag is provided, in accordance with this invention, with means for carrying a name and address card.

Figure 2 is a front view of fastener upon a 35 larger scale and detached from the body of the bag, showing the frame member with which it is provided and the name and address card fitted therein, the celluloid covering provided being partly withdrawn.

Figure 3 is an end view of the fastener and frame member.

Figure 4 illustrates a rear view.

Figure 5 represents a vertical section through the fastener and frame when 45 detached from the bag.

Figure 6 is a front view showing the name and address card and the celluloid covering removed from the frame.

Figure 7 is a horizontal section on the line 50 7—7, Figure 6.

The same reference numerals indicate corresponding parts in each of the figures.

Referring to the drawings, the hand bag is provided with a fastener of the usual type, comprising a projection or stud element 1 on the flap 2 of the bag which is adapted to be engaged within an opening or socket in the other part of the fastener which is fixed upon the front of the body portion 3 of the bag, as illustrated in Figure 1. The part of 55 the fastener upon the body portion of the bag comprises front and rear plates 4 and 5, the front plate 4 being slightly dished or provided with a narrow flange, and having integral ears 6 at its edge which are bent over 60 on to the rear face of the back-plate 5 so that the two plates are thus secured together. Coincident holes 7 are provided in the two plates which are adapted to receive the stud 1 of the fastener, the hole in the back-plate 65 having a short sleeve or eyelet 8 fitted therein which is provided with a spring-ring 9 adapted to engage a groove around the stud, the said sleeve or eyelet having a flanged inner end which fits between the two plates. 70 According to this invention the back-plate 5 of the fastener is provided with a rectangular integral extension 5^a which extends a considerable distance beyond the upper edge of the front plate. This extension 5^a of the 75 back-plate is adapted to carry a frame member or holder 10 arranged to carry a card or label 11 upon which the name and address of the owner of the bag may be written, the said extension being provided at its ends with 80 integral bent-back prongs 12 which are adapted to be passed through the material of the bag and bent over so as to secure the fastener in position the prongs being preferably 85 bent down on to a metal plate fitted against the inner face of the material. The frame member or holder 10 which carries the name and address card is likewise of a rectangular formation, of a similar size to the extended portion 5^a of the fastener, being in the form 90 of a sheet metal plate having an inwardly-bent flange 13 formed along three of its edges, so that the one end of the frame member is left open for the insertion of the name and address card 11. The said frame mem- 95 ber 10 is provided with a slot 14 through which 100

ber 10 is provided with a pair of rearwardly-extending struck-up ears 14 which are passed through slots in the extension 5^a of the fastener, the ears being bent back on to the rear face of the extension so that the frame member or holder 10 is thus rigidly secured to the latter. After the fastener has been secured to the body portion 3 of the hand bag by means of the prongs 12, the card or label 11 for bearing the name and address of the owner is slid in beneath the flanges 13 of the frame member through the open end of the latter. A rectangular celluloid covering 15 is then fitted above the card or label, being likewise slid beneath the flanges, the outer end of the celluloid being provided with a metal edging 16 which serves to close the end of the frame and also facilitates the removal of the covering when desired.

By arranging the frame member or holder for the name and address card above the fastener upon the body part of the bag, as above described, it is covered by the flap 2 of the bag when the latter is closed, so that it is hidden from view; it is, however, readily seen immediately the bag is opened.

Instead of the frame member or holder being attached to an integral extension of the back-plate of the fastener it may be attached to an extension of the front plate; or it may be attached to the fastener in any other suitable manner, whilst the fastener portion may be of any other suitable construction.

A frame member or holder of any other suitable construction may also be provided, whilst the said frame member or holder may be of any desired shape and may be arranged beneath or at one side of the fastener portion, instead of being arranged above the latter.

Although the invention has been applied to fasteners for hand bags it is equally applicable to fasteners or locks for purses, attaché cases or the like.

Having fully described my invention, what I desire to claim and secure by Letters Patent is:—

1. An attachment for a purse, hand-bag, attaché-case or like receptacle comprising a flat back plate adapted to be attached to the face of the said receptacle, a receptacle-fastening element carried by the front face of said back plate, and a flanged holder for an identification card said holder also being carried by the said front face of the back plate close to and flush with said fastening element.

2. An attachment for a purse, hand-bag, attaché-case or like receptacle comprising a back plate adapted to be attached to the face of the said receptacle said plate having an aperture, a flanged and apertured front plate applied to the front face of the back plate with the edge of the flange engaging the said face so as to form a stud-receiving socket fastener element, the said flange having integral

ears clenched to engage the back plate, and a flanged holder for an identification device secured to the front face of the said back plate in juxtaposition to the socket fastener element and substantially flush therewith.

3. An attachment for a purse, hand-bag, attaché-case or like receptacle and adapted to be attached to the outside of the body part thereof, comprising a back-plate having means whereby it may be secured to said body part, a hollow forwardly-projecting casing of a socket fastener element secured to the lower part of the front face of said back plate, said casing having a flat horizontal top edge, and a self-contained card holder, comprising a flat plate with forwardly-overhanging card-receiving edges, attached to the upper part of the front face of said back plate with its lower edge contiguous to and engaging the top horizontal edge of the lower casing, the said card holder being of the same thickness as the lower casing so as to be flush therewith.

In testimony whereof I have hereunto set my hand.

CLARENCE FLINT.
